UNITED STATES PATENT OFFICE.

BENJAMINE F. SALMON, OF FREELAND, PENNSYLVANIA.

PROTECTING ATTACHMENT FOR LEGS OF TROUSERS.

SPECIFICATION forming part of Letters Patent No. 694,200, dated February 25, 1902.

Application filed April 15, 1901. Serial No. 55,866. (No model.)

To all whom it may concern:

Be it known that I, BENJAMINE F. SALMON, a citizen of the United States, and a resident of Freeland, in the county of Luzerne and State of Pennsylvania, have invented new and useful Improvements in Protecting Attachments for the Legs of Trouser, of which the following is a full, clear, and exact description.

10 The object of this invention is to provide a novel, simple, and inexpensive attachment for the legs of trousers worn by miners or others working in wet places, and is especially adapted for the protection of the lower portions of the ordinary trousers-legs, so as to prevent them from becoming damp while the wearer is working on a wet floor and wherein at times he has to kneel and prevent pieces of any hard or soft substance from dropping 15 into the top of the boot and which often injures the foot.

The invention consists in the novel construction and combination of parts, as is hereinafter described, and defined in the appended 20 claim.

Reference is to be had to the accompanying drawings, forming a part of this specification, in which similar characters of reference indicate corresponding parts in all the figures.

25 Figure 1 is a partly-sectional side view of the improvement in place on the trousers-leg. Fig. 2 is an enlarged side view of the improvement applied to the trousers-leg, and Fig. 3 is a front view of the invention detached and 30 in extended condition.

In the drawings, 10 indicates one of the legs of ordinary trousers, such as are worn by miners or other workmen, for whom the invention is available as a protection against injurious wear of the trousers and to prevent 35 the legs of such a garment from being saturated with moisture to the detriment of the health of the wearer.

The boot 11 is one of a pair such as miners 40 usually wear, having legs that extend up to the knee of the leg whereon the boot is drawn for its protection. Usually a miner folds the lower portion of each trousers-leg 10 around the calf of a respective lower limb of his body 45 before the boot 11 is drawn upon the leg it is provided for, thus filling up the space in the boot-leg 11^a, as shown in Fig. 1, this folded

adjustment of the trousers-legs in the boot-legs serving to prevent a slopping action of the boot and also keep the lower limbs of the 55 wearer warm. When the miner is working either in a stooping or erect posture, the boot-legs serve to keep his lower limbs dry if he is working where the floor of the mine is wet, as is frequently the case if the operation is 60 being conducted in a low level of the mine, and prevent pieces of coal or other substances from entering the top of the boot.

It is often necessary for a miner to kneel down on the wet floor of a mine, and as this 65 posture immerses the open upper edge of the boot-tops, as well as the knees of his trousers, in the water it will be obvious that the lower limbs of the operator will quickly become chilled by the cold mine-water that saturates 70 the lower portions of the trousers-legs 10.

My improvement effectively prevents the entrance of coal, water, or other substance into the tops of a pair of boots such as shown at 11 in Fig. 1, and consists of the following 75 details of construction: A waterproof cap-piece 12 is provided for each trousers-leg, and the contour of its upper portion is such as to adapt it to cover the knee of the trousers-leg and extend a suitable distance above the 80 same, as represented in the drawings. Each cap-piece 12 is sewed at its edge upon a respective leg of the trousers 10 and, as shown at 12^a, an integral portion of the device for each trousers-leg extends in tubular form 85 down from the part 12, so as to incase the top portion of the boot-leg 11^a.

The material for each knee-protector and boot-top closer is made of such length in the tubular portion 12^a thereof as to fit closely 90 around the open top portion of the boot-leg, with which it engages and outside of which it depends, and, if desired, any suitable means may be employed to draw the free lower edge of each tubular portion 12^a more closely 95 against the leg of the boot. Preferably the portion under the knee of the wearer is left unclosed, so as to permit the same to be readily turned up when the boots are drawn on. As the material of which the protectors are 100 made is flexible, the tubular portion 12^a may be turned up over the knee when the boot is to be drawn on the leg, and after the boot is donned by the wearer the tubular portions are

to be turned down for the incasement of the boot-legs at their tops, as hereinbefore described.

It will be seen that when the legs of a person's trousers are provided with the improvement the knee portions of said garment will be reinforced in a manner which will prevent them from injury when the wearer kneels upon rough fragments of coal or other mineral he is engaged in mining, and, as before mentioned, the lower limbs of the operator are fully protected from intrusion of water into the top of his boots while he is in a standing or kneeling posture.

Having thus described my invention, I claim as new and desire to secure by Letters Patent—

As a new article of manufacture a pair of trousers having its leg portions provided on

their outer sides at the front with a knee-protector whose lower end is free or detached from the trousers-legs and forms a flap to fit over and incase the upper end of a boot-leg, when the latter is fitted over the trousers, such flap having its rear ends disconnected or unclosed to facilitate the turning up of the flap when the boots are drawn on and the turning down of the flap over the upper end of the boot-leg, all substantially as and for the purposes set forth.

In testimony whereof I have signed my name to this specification in the presence of two subscribing witnesses.

BENJAMINE F. SALMON.
